No. 37,185.

Patented October 11, 1904.

UNITED STATES PATENT OFFICE.

MARGARET M. HARDING, OF MONROVIA, CALIFORNIA.

DESIGN FOR A PORTIÈRE.

SPECIFICATION forming part of Design No. 37,185, dated October 11, 1904.

Application filed September 14, 1904. Serial No. 224,474. Term of patent 7 years.

To all whom it may concern:

Be it known that I, MARGARET M. HARDING, a citizen of the United States, residing at Monrovia, in the county of Los Angeles and State of California, have invented a new, original, and ornamental Design for a Portière, of which the following is a specification, reference being had to the accompanying drawing, forming a part thereof.

10 This invention relates to an ornamental, unique, and novel design of portière, substantially as shown in the accompanying drawing, which is an elevation.

What I claim as new is—

The ornamental design for a portière, substantially as shown.

MARGARET M. HARDING. [L. s.]
